UNITED STATES PATENT OFFICE.

WILFRID E. DIEGEL, OF RIVER ROUGE, MICHIGAN.

GAME.

Application filed July 29, 1925. Serial No. 46,743.

To all whom it may concern:

Be it known that WILFRID E. DIEGEL, a citizen of the United States, residing at River Rouge, in the county of Wayne and State of Michigan, has invented certain new and useful Improvements in Games, of which the following is a specification:

This invention is a game designed to be played upon a specially prepared board with counters and other elements, and the general object is to provide an attractive and entertaining game apparatus for indoor amusement.

In the drawing

Figure 1 is a plan view of the game board;

Figure 2 is a longitudinal, vertical section;

Figure 3 is a detail of the interference triangle;

Figure 4 is a detail of the ball;

Figure 5 is a detail of one of the counters;

Figure 6 is a detail of the spring plunger;

Figure 7 is a detail of the pocket structure.

This game includes a rectangular, horizontally disposed field board 1, enclosed by vertical sides and ends 2, which sides and ends both rise above and depend below the plane of the field board, so that the latter is held in a somewhat elevated position and there is a space left beneath the same. The upper surface of this field board is demarcated and divided into two sections, a medial section 3 and an outlying section 7 which embraces the

medial section 3 on three sides. These two sections are painted and colored differently from each other for the sake of distinction in the purpose of the game. One end of the medial section 3 extends out to the end of the board and coincides with the end of the section 7, while the opposite end falls short of the opposite end of the board, as shown in Figure 1.

At the sides and at one end of the structure, a number of pockets 4 are formed, there being four pockets at each side and one at the end of the section 3 which extends clear to the end of the board, and these pockets are numbered as shown. These pockets

may be formed in any conventional manner, as by cutting out semi-circular sections 5 from the field board and tacking in bags 6. The mouths of the pockets are of course to be flush with the upper surface of the field board 1. At that end of the field board 1 covered by the colored section 7, a spring-set

catapult 8 is mounted. For this purpose a support 9 is fastened to the board 1, slightly spaced from the end thereof, and aligned holes 10 are bored through the end piece 2 and the said support 9. The catapult bar 11 is then slidingly mounted through these holes, and a propulsive coil spring 12 is operatively mounted over the bar 11 and braced between a cross pin 13 set through the bar 11 and the said end piece. The accessories of the board comprise a ball 14 of any suitable material, an interference triangle 15 and a plurality of counters 16.

Various forms of play may be devised, using the apparatus as described. In the form contemplated now by the inventor, each player is provided with an equal number of counters similar to 16. Each player then successively places the triangle 15 at any point he desires upon and within the medial field section 3, places the ball 14 in advance of the catapult bar 11, and shoots the ball across the field. Should the ball roll into any one of the pockets, each of the other players delivers to the player making the shot, the number of counters called or represented by the serial number of that pocket. The play is continued until each player in turn has had fifteen shots. The one then holding the most counters is the winner. In case a player loses all his counters before getting fifteen shots, he is "out" of that game.

While I have herein described a certain specific manner and method of constructing and assembling the elements of my invention, it is understood that I may vary from the same in minor details, not departing from the spirit of my invention, so as best to construct a practical device for the purpose intended, as defined in the appended claims.

I claim:

1. A game apparatus, comprising in combination a rectangular field board with raised sides and ends, the field including a medial section extending out to one end of the board, and a differentiated outlying section which embraces the medial section on three sides, the said board having a plurality of numbered pockets arranged upon two sides and at the outer end of the medial field section, the mouths of the said pockets being flush with the surface of the field board; a catapult at the end of the board covered by the said outlying field section; a ball adapted to be driven by the catapult

into said pockets; an interference triangle for placing upon the said medial section; and a plurality of counters for checking the status of the players.

- 5 2. A game apparatus, comprising in combination an enclosed rectangular field including differentiated medial and outlying field sections; a plurality of numbered pockets arranged around three sides of the field; an interference triangle for placing upon the said medial section; a ball; a plurality of counters for checking the status of the players; and mechanical means for propelling the ball over the field.
- 10 3. A game apparatus, comprising in combination a field board enclosed at the sides, the field of the board including medial and outlying sections; pockets arranged around the sides of the board; an interference triangle for locating upon the medial field section; a ball for rolling over the board
- 15
- 20

against said triangle and into said pockets; and a plurality of counters for checking the game.

4. A game apparatus, comprising in combination a field board having differently colored medial and outlying field sections, the medial section coinciding at one side with the side of the outlying section; nine serially numbered pockets mounted upon three sides of the field board, the middle portion of the outlying section, however, being left open; a catapult mounted at the edge of said middle portion of the said outlying section; an interference triangle for locating upon the said medial section; a ball adapted to be driven over the board by the catapult and to roll into said pockets; and a plurality of counters.

In testimony whereof I affix my signature.

WILFRID E. DIEGEL.
